UNITED STATES PATENT OFFICE.

JOHN C. WILLIAMS, OF SCOTLAND NECK, NORTH CAROLINA.

MACHINE FOR MEASURING BAGGING AND OTHER FABRICS.

SPECIFICATION forming part of Letters Patent No. 280,547, dated July 2, 1883.

Application filed November 11, 1882. (Model.)

To all whom it may concern:

Be it known that I, JOHN C. WILLIAMS, of Scotland Neck, in the county of Halifax and State of North Carolina, have invented a new and Improved Machine for Measuring Bagging and other Fabrics, of which the following is a full, clear, and exact description.

The object of my invention is to provide a new and improved machine for measuring cotton bagging, carpets, and other fabrics accurately and rapidly.

Reference is to be had to the accompanying drawings, forming part of this specification, in which similar letters of reference indicate corresponding parts in all the figures.

Figure 1 is a longitudinal sectional elevation of my improved measuring-machine. Fig. 2 is a longitudinal elevation of the same. Fig. 3 is a plan view of the same.

20 The material to be measured is contained on a beam, A, journaled in a frame, B, and from the said beam A the fabric passes over a guide-roller, C, and between two feed rollers D and E, of which the former is journaled in the top of the frame B, and the latter roller, E, is journaled in a frame or box, F, pivoted to the top of the frame B. The frame F is provided with an arm, F', at its free end, from which arm a weight, G, is adjustably 25 suspended, which weight presses the roller E on the roller D and produces the required friction. A small cog-wheel, H, on the shaft of the bottom feed-roller, D, engages with a larger cog-wheel, J, on a crank-shaft, K. A drum, L, having a roughened surface, is mounted on a shaft, M, on one end of which is mounted a cog-wheel, N, which engages with a cog-wheel, O, provided with a pointer or hand, P, above a dial, Q, which dial is subdivided into feet, inches, &c., on a suitable scale. The bearings of the shaft M are such as to permit of vertical adjustment of the shaft. A hook, S, of a lever, T, is passed over the shaft M, and from the free end of the 30 lever T a weight, W, is suspended adjustably, which weight presses the roughened drum L on the fabric.

40 The operation is as follows: The roller E is raised, the end of the fabric is placed between the rollers E D, and the crank-shaft K is turned, whereby the rollers D E will draw the fabric through the machine in the direction of the arrow a', whereby the drum L will be rotated in the direction of the arrow b'.

The cog-wheel, N rotates the cog-wheel O, 55 and the pointer or hand P shows the number of revolutions of the drum and also parts of revolutions, and, if the circumference of the drum L is known, the length of the fabric can easily be ascertained. The circumference of 60 the drum is to be equal to one or more yards. Cotton bagging, carpets, &c., can be measured very easily and rapidly by simply drawing them through the machine.

By means of the weight G the friction of the 65 rollers D and E can be so regulated that the fabric cannot slip between the two rollers.

Having thus described my invention, what I claim as new, and desire to secure by Letters Patent, is—

1. In a fabric-measurer, the surface-roughened drum L and a subjacent bed in close proximity thereto, combined with suitable means for holding the fabric on one side of the drum and suitable means on the other 75 side for drawing it, whereby the pressure upon the fabric between the drum and bed will cause the surface of the drum to move exactly with that of the fabric.

2. The hook S and the lever T, the latter 80 attached between its fulcrumed end and its weighted end to the shank of the former, in combination with the measuring-roll shaft M, arranged above said lever, to hold the measuring-roll down on the fabric, as described.

3. In a measuring-machine, the combination, with the feed-roller D, of the feed-roller E, the pivoted frame F, the arm F', the weight G, and a measuring-drum, L, substantially as herein shown and described, and for the purpose set forth.

4. In a measuring-machine, the combination, with the feed-rollers D E, of the measuring-drum L, the lever T, the weight W, the cog-wheels N O, the dial Q, and the hand P, 95 substantially as herein shown and described, and for the purpose set forth.

5. The frame F, having an extension-arm, F', to which is appended an adjustable weight, in combination with the shaft of the upper 100 drawing-roll, whereby the tractional power to be exerted on the fabric may be regulated by movement of the weight.

JOHN CORNELIOUS WILLIAMS.
